(57) **CLAIM**

The ornamental design for a flashlight, as shown and described.

DESCRIPTION

FIG. 1 is a perspective view of the flashlight;
FIG. 2 is a top planar view of the flashlight;
FIG. 3 is a bottom planar view of the flashlight;
FIG. 4 is a side end elevational view of the flashlight, the opposite side end elevational view being a mirror image thereof;

FIG. 5 is a back end view of the flashlight; and,

FIG. 6 is a front end view of the flashlight.

The broken lines are shown for illustrative purposes only and form no part of the claimed design.
